UNITED STATES PATENT OFFICE.

FRANK WIGGINS, OF KNOXVILLE, TENNESSEE.

MATRIX AND MATRIX-HOLDER.

1,378,748.

Specification of Letters Patent. Patented May 17, 1921.

Application filed January 15, 1921. Serial No. 437,543.

To all whom it may concern:

Be it known that I, FRANK WIGGINS, a citizen of the United States, residing at Knoxville, in the county of Knox and State 5 of Tennessee, have invented certain new and useful Improvements in Matrices and Matrix-Holders, of which the following is a specification.

My invention relates to improvements in 10 dental matrices and the holding means therefor.

The objects of the invention are; to provide a set of matrices, constructed to fit the posterior teeth and to correspond to the 15 shape or curvature thereof, and completely surround the same; to provide a matrix which may be drawn closely about the tooth and burnished to closely contact with the neck of the tooth, to effectively prevent the 20 crowding or passing of the filling restoring material between the matrix and the wall of the tooth, which ordinarily frequently occurs, forming rough edges in contact with the gum, causing gum trouble or diseases; to 25 provide a matrix having engaging elements, adapted for coaction with a resilient holder, the matrix and holder being so constructed and arranged that the mouth may be conveniently closed, when they are used, where- 30 by the opposed tooth may form a natural occlusion in the filling or restoring material, before the same has hardened or set; to provide a resilient holder for the matrix, which will permit of the closing of the mouth or 35 teeth, with the least discomfort to the patient; to provide a connection between the resilient holder and matrix, dispensing with the necessity of the end or ends of the holder extending to the interior of the matrix, 40 whereby the matrix is retained in close contact with the wall of the tooth; to provide a resilient holder which is adapted to extend generally in a vertical direction, when faced upwardly or downwardly, thereby being 45 adapted to lie relatively close to the gum; and to provide a resilient holder which is simple in construction, inexpensive to manufacture, strong and durable.

Other objects and advantages of the in- 50 vention will be apparent during the course of the following description.

In the accompanying drawings forming a part of this specification, and in which like

numerals are employed to designate like parts throughout the same, 55

Figure 1 is a perspective view of the ma- trix and matrix holder, separated,

Fig. 2 is a similar view of the matrix and a slightly different form of matrix holder, 60

Fig. 3 is a perspective view of the matrix in place, with the teeth open,

Fig. 4 is a similar view with the teeth closed, and

Fig. 5 is a perspective view of the second 65 form of matrix holder, opened.

In the drawings, wherein for the purpose of illustration are shown preferred embodiments of my invention, the numeral 10 designates a matrix band, preferably formed of 70 a thin metal strip, sufficiently stiff for ordi- narily retaining its shape, but sufficiently flexible to permit of the same being bur- nished down to closely contact with the wall 75 of the tooth and conform to the curvature of the wall. The matrix band is adapted to pass between two of the adjacent teeth, with its ends lightly overlapping, preferably upon the outside or buccal wall of the tooth. It is preferred that a number of these 80 matrix bands be provided, corresponding to the size and shape of the different posterior teeth, it being desired that a band be ob- tained for each tooth treated, which will completely surround the tooth and have its 85 ends contacting or in close relation. The matrix band is provided at points near and spaced from its ends with curved or crescent shaped openings 11, stamped therein, forming outwardly bent attaching elements or 90 teeth 12, preferably integral with the ma- trix. These attaching elements or teeth are arranged upon the outer side of the tooth.

The resilient holding member comprises a U-shaped body portion 13 including an 95 intermediate yielding portion 14. The arms of the U-shaped body portion have their upper portions twisted and arranged in a plane at substantially a right angle to the portion 14. It is therefore obvious that the 100 arms do not yield readily, when spread apart, but that the portion 14 performs a yielding function. The upper ends of the arms, are bent transversely and inwardly, into flat jaws 15, having recesses or notches 105 16, for the reception of the elements or teeth

12. The U-shaped body is tensioned to spring inwardly.

In Figs. 2 and 5, I have shown a different form of resilient matrix holder, comprising a U-shaped body portion 16, including a yielding portion 17, and twisted arms 18, disposed at a right angle thereto. At their ends, these arms have extensions 19, which cross, and carry inwardly directed jaws 20.

10 The U-shaped body portion 16 is tensioned whereby its arms spring outwardly, causing the jaws 20 to move inwardly. The jaws 20 may be equipped with the notches 16.

In use, the matrix band 10, of a suitable shape and size is applied to a posterior tooth 21, preferably with the elements 12 arranged outermost. The holding element 13 may now be employed to contract the matrix band, by engaging the jaws 15 behind and with elements 12, fitting in notches 16. This forms a secure engagement between the two parts of the device. The matrix band may be burnished down upon the tooth, to fit tightly against the same, preventing the possibility of the filling or restoring material passing down between the matrix band and tooth. The holding device, extends generally in a vertical direction, between the gum and cheek, and being generally flat, does not unduly inconvenience the patient, when the teeth are closed, as in Fig. 2, for forming a natural occlusion in the restoring or filling material 22. The use of the other holding device is thought to be obvious.

It is to be understood that the forms of my invention herewith shown and described are to be taken as preferred examples of the same, and that various changes in the shape, size, and arrangement of parts may be resorted to without departing from the spirit of my invention, or the scope of the subjoined claims.

Having thus described my invention, I claim:—

1. A flexible matrix band adapted to extend completely around a tooth with its ends in close relation, said band being provided near said ends with outwardly extending engaging elements stamped there-

from, and a resilient holding member having jaws to engage behind said elements and notches to receive the elements.

2. A flexible matrix band adapted to extend substantially completely around a tooth with its ends in close relation, said band being provided near its ends with attaching elements projecting outwardly beyond the band, and a resilient holding member having jaws provided with notches adapted to receive therein the attaching elements, whereby the jaws and attaching elements have an interlocked engagement, the holding member being adapted to be wholly mounted within the mouth upon one side of the teeth.

3. A flexible matrix band adapted to substantially completely surround the tooth with its ends in close relation, an approximately U-shaped holding member arranged upon one side of the tooth and embodying spaced resilient arms, said approximately U-shaped holding member being adapted to permit of the teeth being closed, and means for effecting a positive and readily detachable interlocking engagement between the arms of the holding member and the end portions of the matrix band, the arms being detached from the end portions of the matrix band by a lateral movement of said arms.

4. A flexible matrix band adapted to extend around a tooth, an approximately U-shaped holding member having an intermediate yielding portion and arms twisted longitudinally to assume a position at right angles thereto, said U-shaped member being generally flat and adapted for arrangement in a vertical position when in use, said arms having transverse jaws, and engaging elements carried by the matrix band near its ends for coaction with the jaws.

5. A matrix band holding member comprising a resilient U-shaped member having its arms twisted and provided at the ends of the twisted portions with jaws having notches.

In testimony whereof I affix my signature.

FRANK WIGGINS.
